UNITED STATES PATENT OFFICE.

JEAN DELPHICE OLIGNY, OF MONTREAL, QUEBEC, CANADA, ASSIGNOR TO PEAT GAS AND COAL COMPANY, OF MONTREAL, CANADA, A CORPORATION OF MAINE.

PEAT-GAS-PRODUCING PROCESS.

977,469.

Specification of Letters Patent.

Patented Dec. 6, 1910.

Application filed February 4, 1909. Serial No. 476,115.

To all whom it may concern:

Be it known that I, JEAN DELPHICE OLIGNY, resident of 37^A St. Augustin street, in the city and district of Montreal, in the 5 Province of Quebec, in the Dominion of Canada, a subject of the King of Great Britain, have invented certain new and useful Improvements in Peat-Gas-Producing Processes; and I do hereby declare that the 10 following is a full, clear, and exact description of the same.

The invention relates to a peat gas producing process, as described in the present specification and illustrated in the accompanying drawing that forms part of the 15 same.

The invention consists essentially in the various steps hereinafter more particularly set forth and pointed out in the claim.

20 The object of the invention is to utilize the peat, so readily obtainable, in the most economical manner, that is through the cheap production of a gas having illuminating as well as heat and power producing 25 properties.

The drawing is a view showing merely the outline of the parts to the plant, used in this process.

The first step in the process is destroying 30 the capillary nature of the peat by placing it under crushing rollers 1 or in fact any suitable crushing means and during this step saturating the said peat with petroleum or other hydro-carbonaceous oil 2, then inserting 35 said peat so pulped and charged with petroleum into a retort 3 heated by the furnace 3^A and baking, until the mass becomes thoroughly coked and relieved of all the 40 gas and during this step injecting air from the compressed air reservoir 9 into the said retort, thus warming said air thoroughly and at the same time lading the gas with air, as warm air will readily mix with the rich peat gas, then passing the gas from 45 said retort through a carbureting chamber 4 containing tar preferably obtained as a by-product from the peat itself, then passing the gas through a suitable pipe 5 and through condensing arrangements 6 and 50 dropping the by-products in passage into suitable receptacles 7 and finally passing the gas into a gasometer or gas holder 8.

The gas on leaving the retort is, as hereinbefore mentioned, laden with air and in this state reaches the carbureting chamber 55 containing the tar and in this cooled chamber the mixed air and gas is carbureted and much of the tar carried with the gas drops back into the said chamber from above. The overflow of the tar chamber is taken 60 care of by an overflow passage and receptacle 9 and 10.

The condensing of the gas further on in the process will cause the exusion therefrom of any further excess of tar and also other 65 by-products, as also later on in its flow, the exusion of alcohol, the gas finally reaching the gas holder or gasometer with its illuminating, heating and explosive properties intact and generally in first class commercial 70 condition.

The tar in the carbureting chamber is, of course, in a liquid state as it is being continually fed from the tar by-product dripping from the gas, ascending after it has 75 passed through the said chamber, the overflow of course flowing through the said overflow passage, which passage has a suitable trap therein for sealing purposes.

What I claim as my invention is: 80

The herein described peat gas producing process, consisting in first taking the peat in its natural moist state and crushing, and sprinkling it during said crushing with petroleum oil thus destroying the capillary nature of said peat and producing a pulpy petroleum charged substance, then subjecting said substance to intense heat, then injecting air by forced draft to mingle with the gas from said peat during the step of coking 90 and thus lading the gas with air, then passing the air laden gas through liquid tar for carbureting purposes, then withdrawing the by-products by condensation and finally passing the gas into a suitable holder. 95

Signed at the city and district of Montreal, in the Province of Quebec, in the Dominion of Canada, this 12th day of January, 1909.

JEAN DELPHICE OLIGNY.
